UNITED STATES PATENT OFFICE.

WILLARD O. LATHROP, OF CINCINNATI, OHIO.

BRACING DEVICE FOR SPRING-BED STRUCTURES.

Application filed December 17, 1926. Serial No. 155,535.

This invention relates especially to spring-beds of the vertically-actuating or perpendicular spiral type.

Heretofore, these beds have been more or less defective in that when the spirals were compressed under the weight of the occupant of the bed the general assembly or cluster of them was under more or less torsional or distorting horizontal movement, both laterally and horizontally otherwise of the bed, and, more especially, when the said occupant started to lie down upon them, or when, otherwise, making a shifting-position on them and thus throwing them out of their proper normal desired perpendicular actuating-alignment in their supporting or containing frame.

To remedy the said fault and to otherwise prevent lateral or distorting torsional longitudinal actuation of the spirals, or any undue sagging, spreading, or sidewise-movement thereof, in a simple, convenient, economical and effective manner, are the prime and essential objects and features of my invention herein, which is composed of a resilient wire brace-member having an angulated pair of somewhat similar straight spring-arms that are integrally-connected by means of a coil-member and suitably located in the ordinary assembly or cluster of vertically-supported spirals so that one spring-arm (the longer of the pair) is connected to the heavy border-wire or frame in the upper deck of the spring-structure and the other spring-arm (the shorter of the pair) is connected to the transverse slat-bars located in the lower deck of said spring-structure, such brace-member being provided in multiple over the spiral-clustered interior of the spring-structure, within its upper and lower decks and extending both laterally and longitudinally in a somewhat strong resilient manner so that the spirals are supported upright and there is no motion in them other than a cushioning, resilient or elastic one, and thereby preventing any undue sagging, spreading or sidewise-movement of the spirals at any time while in use, and making up a bed-spring structure that is at once simple, economical and effective against all sidewise collapse and also, preserving a straight perpendicular riding of the assembled spirals within their connecting tie-wires used in the enclosing border wire or frame.

In the accompanying sheet of drawings—

Figure 1 is a plan view of a spring-bed structure embodying my invention, showing it in fragmentary form so as to illustrate the

four corners thereof and as many of the brace-members in the said corners for stabilizing the structure in those parts thereof more particularly; Fig. 2, a transverse section taken 60 on the irregular angled dotted-line 2, 2, of Fig. 1; and Fig. 3, a detail perspective view of the peculiar structure of brace-member embodying the invention herein, showing it, apart from the bed-spring structure. 65

A indicates the main-frame or the heavy border-wire comprising same and formed, as usual, in rectangular outline, in bed-spring structures of the class first above-named.

B indicates the usual angle-iron frame or 70 lower deck to which is connected by means of rivets C, the opposite ends of the series of transverse slat-bars D, in the ordinary manner.

In Fig. 2 is seen how the said slat-bars D are 75 each made of thin bar metal that is arranged longitudinal edge-up and with its opposite ends half-twisted into a horizontal attaching-member d that is secured by means of said rivets C to the underside of the upper horizontal portion b of said angle-iron B, said rivets also securing the lower end of the outermost or border rows of upright spirals E of the rows of spirals that form the cluster or assembly of springs used in the bed-spring 80 structure, F indicating the main body of the 85 cluster or array of internal spirals within the limits of said outermost border-rows E, as customary.

To properly uphold all the spirals in a perpendicular state is the prime object of my invention herein and it is best accomplished by means of a suitable number of resilient brace-arms scattered over the interior of the bed-spring structure, as partly shown in the fragmentary or sectioned bed-spring structure seen in Fig. 1, the specific form of brace-member or brace-arm unit, as it were, being especially well shown in Fig. 3 and composed of a main or long resilient spring-arm G whose inner 90 end is integrally-coiled at H and thence extends onwardly and at an acute-angle into a lesser or auxiliary resilient spring-arm I, with a U-shape bend or bight J lying between the said coiled-portion H and the outer pendent hook-end a. The extreme outer end of the said main spring-arm G is formed into a hook-eye g that encircles the border-wire A for fastening-engagement, the said extreme outer pendent hook-end a of the auxiliary 95 spring-arm I being provided for fastening engagement with the lower end of the spiral 100 105 110

F and in contact-engagement with the vertical face of the upper edge of the cross-slat D, said contact engagement being as seen (dotted) in Fig. 2, but the end of the arm I being caught in the lower coil or base of the spiral F, as seen in Fig. 1.

In use, the expansive stress of the coil-connected spring or resilient brace-arms G and I, owing to the main arm G being pivotally-connected to the border-wire A and the said arm G being arranged at an oblique or inclined-line down toward the coil-portion H for placing the said auxiliary-member I at the foot of the brace device and anchoring or resting on the upper edge of the slat-bar D, forms a thrust or take-up that counteracts any tendency of the vertical spirals to sag or collapse sidewise, but, on the other hand, determines the full perpendicular resilient support and action of all the spirals within the border frame of the spring-structure for the proper cushioning-effect of the bed for the occupant thereof. The slanting arrangement of the brace-arms fully effects the perpendicular action of the upper deck of the spring-structure on its lower deck and no lateral movement of any consequence results or can take place.

I claim:—

In a bed-spring structure, the combination

with a main or border frame, a lower angle-iron sub-frame, a series of transverse slat-bars mounted on the said lower angle-iron sub-frame, an inner cluster of upright spirals mounted on the said transverse slat-bars, means by which upper coils of the spirals are connected together and to the said border frame, and a plurality of resilient expansible brace-members distributed throughout the said inner cluster of spirals and adapted to sustain the latter and the border spirals in a perpendicular manner against sagging or any undue lateral movement, and each brace-member comprising a main long spring-arm, a U-shaped bight, an integral connecting coil between the arm and the bight, an auxiliary short spring-arm extending beyond the bight and lying at an angle to the main arm, said main arm having means by which it is attached to the border frame and thence extending inwardly and downwardly, said bight encircling the bottom of one of said spirals and resting on a slat-bar and said short arm extending to and engaged with an adjacent slat-bar, substantially as shown and described.

In testimony whereof I hereunto affix my signature.

WILLARD O. LATHROP.
